US00D523324S

(12) **United States Design Patent** (10) **Patent No.:** **US D523,324 S**
(45) **Date of Patent:** **** Jun. 20, 2006**

(54) **SECURE LOCK**

(75) Inventors: **Shawn W. Miller**, Columbia, SC (US);
David Rocheleau, Lexington, SC (US);
Mohammad R. Sadeghi, Columbia, SC (US);
Walter Zahn, Columbia, SC (US);
Bernd Hansen, Laufen (DE)

(73) Assignee: **Holopack International Corp.**,
Columbia, SC (US)

(**) Term: **14 Years**

(21) Appl. No.: **29/232,966**

(22) Filed: **Jun. 24, 2005**

Related U.S. Application Data

(63) Continuation of application No. 29/220,198, filed on Dec. 28, 2004, now abandoned.

(51) **LOC (8) Cl.** **08-07**

(52) **U.S. Cl.** **D8/330; D8/331**

(58) **Field of Classification Search** **D8/330, D8/331, 398, 394, 343, 499; D9/686, 687, D9/688, 740, 742, 744; 70/57.1, 416, 465, 70/466, 431, 419, 422, DIG. 26; 220/260, 220/265, 266, 277; 215/40.48**

See application file for complete search history.
